CHARGE FORMING MECHANISM

Pietro Maniscalco, Toledo, Ohio

Application August 28, 1936, Serial No. 98,295

15 Claims. (Cl. 123—127)

This invention relates to a new and improved charge forming mechanism.

The invention presented in this application is an improvement over that shown in my prior application for Semi-convertible fuel oil engine, Serial No. 44,239, filed October 9, 1935.

One of the objects of this invention is to provide an internal combustion engine which is particularly adapted for use in automobiles, and which is arranged to be operated with heavy liquid hydrocarbon fuel, such as crude oil, and also with a lighter hydrocarbon fuel, such as gasoline, whereby the gasoline may be used as a priming fluid for the heavier oil, and may also be used alone to operate the engine; and whereby the engine is furthermore adapted to utilize alcohol as a fuel, either with or without the gasoline and/or the fuel oil.

Another object is to provide such an engine with suitable mechanism whereby the exhaust gas is utilized to first preheat and then to vaporize the fuel oil, and is thereafter furthermore utilized to preheat the oil fuel mixture and likewise the gasoline fuel mixture, before either mixture enters the precompressing means.

A further object is to provide such an engine which comprises double fuel feeding means both provided with valve control means and wherein said control means are interconnected, so that the fuel supply thru the two feed lines can be controlled by one operating means, like the usual control rod leading to the customary foot pedal used in the modern automobile.

A still further object is to provide such an engine which comprises control means whereby the feeding of the lighter fuel will be stopped and of the heavier fuel will be started when the mechanism is sufficiently heated to vaporize the latter, and which also comprises link means for connecting the two valve control means, whereby to control the feeding of the two fuels together, as by the customary operating means now used for controlling the feeding of gasoline fuel in automobiles.

These and various other objects and advantages are attained with this invention, as will become apparent from the following description, taken in connection with the accompanying drawings wherein the invention is shown in its preferred form of construction, it being understood that various other forms and modifications may be adopted for carrying out the objects and purposes of this invention.

In the drawings:

Fig. 1 is an end elevational view of an engine

embodiment this invention in its preferred form of construction, with parts broken away and in section.

Fig. 2 is a side elevational view of this invention parts being broken away and in section. 5

Fig. 3 is a plan view thereof, with parts broken away to show the oil vaporizing and preheating means.

In the drawings this invention is illustrated in its preferred form of construction, embodied in 10 an internal combustion engine adapted to utilize as its fuel either light or heavy liquid hydrocarbon, and also alcohol, so that fuels may be used together or separately, as may be found advantageous under different conditions. This construction comprises a combustion cylinder 6 containing a piston 7 therein, and a precompressing cylinder 8 containing a piston 9 therein and wherein the fuel mixture is compressed and preheated. A storage chamber 10 operatively connects the two cylinders adapted to store and convey the required amount of precompressed fuel mixture from cylinder 8 to cylinder 6 at proper temperature and pressure, to provide a full power stroke of piston 7. Cooling jackets 11 are provided around the two cylinders and communicate with a cooling jacket 12 provided around storage chamber 10, while a hot water return pipe 13 conducts the hot water to a suitable radiator, a suitable inlet for the water to the jacket being 30 similarly provided.

A carburetor 15 has the gasoline fuel conveyed thereto thru a supply line 16, and has air conveyed thereto thru an intake and filter means 17. The carburetor is connected by a neck 18 with 35 the intake end 19 of manifold 20. A control valve 21 is provided in neck 18 and is operated by a lever 22. From intake end 19 the pre-mixed fuel charge passes into diverging intake branches 23 of the manifold, flowing therefrom 40 into the entrance chambers 24 provided at the upper ends of cylinders 8. A valve element 25 closes the valve seat at the upper end of cylinder 8 and is movable to admit the fuel mixture from chamber 24 to said cylinder. 45

The means provided for operating these valves includes a spring 26 on the outer end of each valve stem 27 to urge the valve to its closed position, when the down stroke of piston 9 is completed. 50

A cam shaft 28 is journalled in brackets 29 and 30 provided on the engine, and has cams 31 thereon for operating valve stems 27 to open the valves 25. Said cam shaft 28 is driven by the crank shaft 32, as by means of a driving disk 33 55

on crank shaft 32 and a link 34 connected thereto and to a driven disk 35 secured to the cam shaft 28. Disks 33 and 35 have grooves 33' and 35' provided around the circumference adapted to receive a V-shaped belt, to provide an additional driving means for overcoming any starting inertia that may occur due to link 34.

A valve 38 on a stem 39 is urged by a spring 40 to the closed position on its valve seat, thereby closing communication between cylinder 8 and chamber 10. This holds valve 38 closed during the main upward stroke of piston 9, so that the mixture in cylinder 8 will be suitably compressed, and the valve will then open when the proper pressure of the mixture is reached. The pre-heated and precompressed fuel mixture then enters chamber 10, and at the end of the upward stroke of piston 9 the valve 38 is closed by spring 40, and the mixture is then confined in chamber 10.

A valve 41 closes the valve opening provided at the upper end of cylinder 6, to stop communication between said cylinder and chamber 10. The valve is held closed by a spring 42 on a stem 43, until actuated by an opening mechanism which includes a cam 44 on a cam shaft 45, arranged to actuate a stem 46 adjustably connected to a rod 47 the upper end of which actuates a lever 48 pivoted at 49 on a bracket 50 provided on the cylinder casing. The free end of this lever 48 bears on valve stem 43 to open valve 41 against the action of spring 42, at the proper time for the admission of the fuel mixture to combustion cylinder 6, thru the operation of suitable timing gear means indicated at 51, 51', which are driven by crank shaft 32 in the usual manner.

An exhaust port 54 is provided in the peripheral wall of cylinder 6, and communicates thru a branch conduit 55 with exhaust manifold 56. This port 54 and the operating mechanism for valve 41 are so arranged and timed that the valve starts opening before exhaust port 54 is fully uncovered, thereby assisting the piston in clearing dead gases from said cylinder 6. When the port 54 is closed by piston 7 during its upward stroke, then the combustion cylinder 6 will be filled with a clean fuel mixture fed from storage chamber 10; thereupon lever 48 raises from stem 43 and spring 42 closes valve 41. Piston 7 then completes its upward stroke and the highly compressed mixture is fired by the action of a spark plug 51 mounted in the upper end of the cylinder, piston 9 being forced downward until it clears exhaust port 54 and the burnt gases are ejected into exhaust manifold 56. Relief bosses 58 may also be provided in the junctions of branches 55 with manifold 56.

A piston rod 61 is pivoted to piston 7 and to a crank 62 on crank shaft 32, and a piston rod 63 is pivoted to piston 9 and to an arm 64 off-set laterally from rod 61, thereby providing a definite advance of stroke of the supercharging piston 9 relative to the main piston 7, which permits a dependable control of the admission of fuel thru the valves of the two cylinders.

A safety valve is preferably also provided for storage chamber 10. This comprises a bypass 65 provided in the top part of cylinder 8, connecting chamber 10 with chamber 24, said bypass being closed by a valve 66 urged by a spring 67. The tension of this spring and the action of the valve being adjustable by manipulating an adjusting nut 69, so that the valve will open to admit fuel mixture from chamber 10 to chamber 24 when the pressure in chamber 10 becomes excessive.

Means is provided herein for utilizing the hot exhaust gases from the manifold for preheating and vaporizing the fuel oil and other liquid fuel which is less volatile than gasoline; and for furthermore preheating either of the employed fuel mixtures before entering the precompressing cylinder. This means comprises a preheating casing 71 which encloses the intake manifold, and which is preferably cast integral therewith; also a conduit 72 for conducting the exhaust gases from exhaust manifold 56 to casing 71.

An oil vaporizing unit 73 is mounted adjacent one end of the casing 71, and preferably includes several branch tubes 74 extending downwardly and then horizontally and again converging into a pipe 75 which extends to the intake end 19 of the intake manifold 20.

Vaporizing unit 73 receives its fuel oil thru a feed pipe 76 which has an oil preheating jacket 77 interposed therein between its lower discharge end and its upper receiving end 76', the latter leading from an auxiliary feed tank 78 which is for convenience mounted between cylinders 6 and 8 and chamber 10. The jacket 77 may be extended part ways or the entire length of exhaust gas conduit 72, as best adapted for its intended use, and altho shown as surrounding the exterior of conduit 72 to form a cylindrical oil receiving chamber thereon, it may be otherwise suitably arranged on or within said conduit. As indicated herein, the upper portion 76' of the oil feed pipe conducts the oil into the upper part of the cylindrical or annular jacket 77, and the lower portion 76 of the pipe conducts the preheated oil from the lower end of the jacket to the vaporizing unit. A feed valve 79 is interposed in upper part 76' and is provided with a lever 80 for operating the valve.

An oil sight feed 81 is interposed in the upper portion 76' of the feed pipe, and a control valve 82 is also interposed in feed pipe 76, provided with an operating crank or lever 83.

A baffle plate 84 is provided in the preheating casing 71 to direct the current of hot exhaust gases closely along the manifold branches 23, 45 as shown in Fig. 2.

The hot exhaust gases are thus utilized first, to preheat the crude oil or heavier fuel fed from tank 78 to the vaporizing unit 73; and then to vaporize the preheated oil in said unit; and finally to heat the fuel mixture, whether crude oil fuel, or gasoline fuel, or alcohol used alone or combined with either of the other fuels, while such fuel mixture is passing thru the manifold and before entering the precompressing means. The reserve heat of the exhaust gas is thus effectively utilized, instead of being wasted. A conduit 85 at the far end of the casing serves as outlet means for the exhaust gases thus utilized.

Automatic control means is provided for controlling the admission of fuels thru the two feed conduits 16 and 76 to the cylinders, whereby the feeding of one kind of fuel will be diminished and shut off, while the feeding of the other is increased; so that the flow of light and volatile fuel, like gasoline, will be stopped when the engine is sufficiently heated, and the flow of the heavier and less volatile fuel, like crude oil, is thereupon fed thru the vaporizing unit 73 to the intake manifold. Alcohol may also be used in this engine, and may be carried in tank 78 in place of the crude oil, or admixed with it.

The control means illustrated herein comprises a thermostatic element 87 mounted in the casing 71, for actuating the stem 88 extending beyond 75

the casing, arranged to operate a member 89 pivoted on a bracket 90 on the casing. A rod 91 extends from member 89 to an operating lever 92 on a valve 93 interposed in gasoline supply pipe 16, for controlling the flow of gasoline to the carburetor. A rod 94 extends from operating member 89 to the lever 83 on oil control valve 82 to control the flow of fuel thru feed pipe 76.

The control means includes a spring 95 connected to operating member 89 and to an arm 96 on the casing, so as to urge and hold gasoline control valve 93 in the open position, and to hold oil control valve 82 in the closed position, until the vaporizing unit 73 and the casing 71 are sufficiently heated; whereupon the thermostatic element 87 actuates stem 88 and member 89, so as to close the gasoline control valve 93 and to open the oil control valve 82 for operating the engine with the heavier and less expensive fuel.

Means is provided herein for operating the levers 22 and 80 and thereby the respective control valves 21 and 79 in unison, thru the usual fuel controlling rod provided on the automobile, which is actuated by the usual foot pedal or the like, 20 in the customary manner and as is well understood. This means comprises a rod 97 extending from lever 22 to an arm 98 on a shaft 99 journaled in brackets 100 mounted in the automobile, and being operated by the usual operating rod 30 101 which is actuated thru the foot pedal or the like and is connected to an arm 102 on said shaft 99. A rod 103 extends from arm 102 to an arm 104 of a crank lever 105 which is pivoted on a bracket 106 on the engine, and is connected thru 35 a link 107 to lever 80 of oil feed valve 79. By operating the rod 101, the rods 97 and 103 and 107 will also be operated, to actuate valves 21 and 79 in unison, either to the open or to the closed position. The feeding of the several fuels thru 40 the two feed pipes 16 and 76 is thus readily controlled by the one customary feed member, as the foot pedal.

Manual control means is also provided, in addition to the automatic control means, for 45 controlling the flow of the different fuels thru the two feed pipes 16 and 76 to the cylinders. This control means may, for example, comprise an arm 110 extending from operating member 89, and a rod 111 connected to said arm and to 50 a crank arm 112 secured on one end of a shaft 113 which is journaled in bracket means 114 in the automobile. A crank arm 115 extends from the other end of said shaft 113, and an operating rod 116 extends from said arm towards the position of the driver, adapted to be connected to a suitable hand operated or foot operated member (not shown), as is well understood, whereby 55 to control the two feed valves manually, if preferred or if found necessary.

While I have disclosed certain preferred embodiments of my invention, these are to be taken as illustrative only, as it is capable of change and variation to meet differing conditions and requirements, and I contemplate such modifications as come within the spirit and scope of the appended claims.

I claim:

1. In an internal combustion engine having a combustion cylinder and an intake manifold operatively connected therewith and provided with means for conducting fuel mixture thereto, a control valve in said means, a gasoline supply pipe connected with said means, a fuel oil supply pipe connected with said manifold and having 75 oil vaporizing means interposed therein adjacent

said manifold, a control valve in said pipe, a lever on each valve, operating means connected with said levers, whereby said valves can be opened and closed together manually, a second valve in said fuel oil pipe and a valve in said gasoline pipe, and means connected with the two last said valves for opening one and closing the other simultaneously.

2. In an internal combustion engine having a combustion cylinder and an intake manifold operatively connected therewith, a carburetor and means connecting it with said manifold, a control valve in said means, a fuel oil supply pipe connected with the manifold and provided with a control valve, operating means connecting said control valves whereby to open them together and likewise to close them together, a gasoline supply pipe connected to the carburetor and having a valve thereon, vaporizing means and also a second control valve in said fuel oil pipe, and operating means connected with the two last said valves whereby they can be operated together to open one and close the other.

3. In an internal combustion engine having a combustion cylinder and an intake manifold operatively connected therewith, a carburetor and valve equipped means connecting it with the manifold, a valve equipped fuel oil supply pipe connected with the manifold and provided with a vaporizing unit, means for heating said unit with the exhaust gas from the engine, operating means connected with the two valves for opening and closing them together, a gasoline supply pipe connected to the carburetor and having a control valve therein, a second valve in said fuel oil pipe, means utilizing exhaust gas for preheating the oil in said pipe before entering said vaporizing unit, and operating means connected with the two last said valves whereby one valve may be opened while the other valve is 40 being closed in harmony with the heat in the vaporizing unit.

4. The subject matter set forth in claim 3, and wherein the operating means is provided with thermostatic means for automatically actuating 45 it to close the gasoline valve and open the fuel oil valve when the vaporizing unit is sufficiently heated to vaporize the fuel oil, and means for manually actuating said operating means.

5. In an internal combustion engine having a combustion cylinder and an intake manifold operatively connected therewith, a carburetor and valve equipped means connecting it with the manifold, a valve equipped fuel oil supply pipe connected with the intake end of the manifold 55 and provided with a vaporizing unit, a casing surrounding said unit and manifold, means for conducting exhaust gas from the engine to the casing to heat the unit and also the manifold, means connected with the two valves for opening them 60 together, a gasoline supply pipe connected to the carburetor and having a control valve therein, a second valve in the fuel oil pipe, operating means connected with the two last said valves whereby the gasoline valve may be closed and the oil 65 valve may be opened, thermostatic means in the casing for automatically actuating said operating means and valves when said unit is properly heated, and means connected with the operating means for manually actuating said operating 70 means and valves.

6. In an internal combustion engine having a combustion cylinder and an intake manifold operatively connected therewith, a carburetor and valve equipped means connecting it with the 75

- manifold, a valve equipped fuel oil pipe connected with the manifold and provided with a vaporizing unit, a casing surrounding said unit and manifold, means for conducting exhaust gas from the engine to the casing to heat the unit and the manifold, operating means and means connecting it with the two valves for manually opening them together, a gasoline supply pipe connected with the carburetor and having a valve therein, a second valve in the fuel oil pipe, an operating member mounted on the casing and having means connecting it with the two last said valves, means including a thermosatic element in the casing for automatically actuating said member to close the gasoline pipe valve and open the oil pipe valve when the unit is heated to vaporize the oil, and means extending from said member and having operating means connected therewith for manually operating said member and valves.
7. In an internal combustion engine having a combustion cylinder and an intake manifold operatively connected therewith, a carburetor connected with said manifold and provided with a valve equipped gasoline supply pipe, a valve equipped fuel oil pipe connected with the inlet end of said manifold and having an oil vaporizing unit interposed therein, a casing surrounding the unit and manifold, means conducting exhaust gas from the engine into the casing to flow over the unit and manifold, an operating member mounted on the casing and being connected with the two valves to operate the same, means actuated by the heat in the casing to automatically operate said member for closing the gasoline pipe valve and opening the oil pipe valve when the unit is sufficiently heated to vaporize the oil, and means including an arm extending from said member also rod and link means connected therewith for manually operating said member and valves.
8. In an internal combustion engine including a combustion cylinder and an intake manifold operatively connected therewith, a fuel oil pipe connected with the manifold and having oil vaporizing means therein, a preheating casing enclosing said vaporizing means and manifold, means for conducting exhaust gas from the cylinder into the casing to flow first upon said vaporizing means to vaporize the fuel oil in said means and then to heat the manifold, preheating means connected with said exhaust gas conducting means and being interposed in said fuel oil pipe, adapted to preheat the oil before entering the vaporizing means, and means for controlling the flow of fuel oil thru said pipe.
9. In an internal combustion engine including a combustion cylinder and an intake manifold operatively connected therewith and provided with a priming fluid supply pipe, a fuel oil supply pipe connected with the manifold and having an oil vaporizing unit therein, a preheating casing enclosing said vaporizing unit and manifold, a conduit conducting exhaust gas from the cylinder to the casing to flow first over said unit and then over the manifold for vaporizing the fuel oil in the unit and preheating the fuel mixture in the manifold, a preheating jacket connected with said exhaust conduit and providing a preheating chamber, said chamber being interposed in said fuel oil pipe, adapted to preheat the oil before entering the vaporizing unit, and control means including valves in said supply pipes and means for operating the valves, where-

by the valve in one pipe is opened and in the other pipe is closed.

10. In an internal combustion engine including a combustion cylinder and an intake manifold operatively connected therewith and provided with a gasoline supply pipe, a fuel oil supply pipe connected with the manifold and having an oil vaporizing unit therein, a preheating casing enclosing said vaporizing unit and manifold, a conduit conducting exhaust gas from the cylinder to the casing to flow first over said unit and vaporize the fuel mixture therein and then also heat the manifold, a preheating jacket surrounding said exhaust gas conduit and providing a preheating chamber between its walls and the walls of said conduit, said chamber being interposed in said fuel oil pipe, adapted to preheat the fuel oil before it enters the vaporizing unit, and control means including a valve in each of said pipes also means connecting said valves for operating them to close the gasoline pipe valve and open the fuel oil pipe valve when the oil in the vaporizing unit is sufficiently heated.

11. The subject matter set forth in claim 10 wherein the operating means for the valves is provided with thermostatic means in the casing to automatically actuate the operating means and thereby the valves, and additional means for manually actuating said operating means and valves.

12. In an internal combustion engine including a combustion cylinder and an intake manifold operatively connected therewith and provided with a gasoline supply pipe, a fuel oil supply pipe connected with the manifold and having an oil vaporizing unit therein, a preheating casing enclosing said vaporizing unit and manifold, means conducting exhaust gas from the cylinder to the casing to vaporize the oil in said unit and to preheat the fuel mixture in the manifold, preheating means connected with said exhaust gas conducting means to provide a preheating chamber, said chamber being interposed in the fuel oil pipe, adapted to preheat the oil before entering the vaporizing unit, control means including a valve in each supply pipe and an operating member connected therewith, means automatically actuated by the heat in the casing to operate said member whereby the valve in the gasoline pipe is closed and the valve in the oil pipe is opened when said unit is properly heated, and additional means for manually operating said member and valves.

13. In an internal combustion engine including a combustion cylinder and an intake manifold operatively connected therewith and provided with a gasoline supply pipe, a fuel oil supply pipe connected with the manifold and having an oil vaporizing unit therein, a preheating casing enclosing said vaporizing unit and manifold, a conduit conducting exhaust gas from the cylinder to the casing to vaporize the oil in the unit and to preheat the fuel mixture in the manifold, a preheating jacket connected with said exhaust conduit and providing a preheating chamber adjacent said casing, said chamber being interposed in said fuel oil pipe, adapted to preheat the fuel oil before it enters the vaporizing unit, a control valve in each of said supply pipes, an operating member connected with said valves, automatic means including a thermostatic element in the casing for automatically operating said member to close the gasoline valve and open the oil valve when the oil in said unit is vaporizing, and means connected with said member for manually operating it and said valves.

14. In an internal combustion engine including a combustion cylinder and an intake manifold operatively connected therewith, a carburetor and valve equipped means connecting it with the manifold, a fuel oil supply pipe connected with the manifold and having an oil vaporizing unit therein, operating means connected with the two valves for manually operating them together, a valve equipped gasoline supply pipe connected with the carburetor, a preheating casing enclosing said vaporizing unit and manifold, a conduit conducting exhaust gas from the cylinder to the casing to vaporize the oil in said unit and preheat the fuel mixture in the manifold, a preheating jacket connected with said exhaust gas conduit and providing a preheating chamber between its walls and the walls of the conduit, said chamber being interposed in the fuel oil pipe, adapted to preheat the fuel oil before it enters the vaporizing unit, a second valve in said fuel oil pipe, control means including thermostatic means connected with the two last said valves for automatically closing the gasoline pipe valve

and opening the fuel oil pipe valve when the oil in the unit is vaporizing, and means for manually operating the two last said valves.

15. In an internal combustion engine having a combustion cylinder and an intake manifold operatively connected therewith, a carburetor and means connecting it with said manifold, a control valve in said means, a fuel oil supply pipe connected with said manifold and provided with a control valve therein, operating means connecting said two control valves by the operation of which said valves are opened together and likewise closed together, a gasoline supply pipe connected to the carburetor and having a valve therein, vaporizing means and a second valve provided in said fuel oil pipe, an operating member and means connecting it with the two last said valves whereby they can be operated together to open one and close the other, and thermosensitive means for operating said member and thereby the last said valves automatically to open one and close the other.

PIETRO MANISCALCO.
